OF PHILADELPHIA, PENNSYLVANIA

SAND-RECONDITIONING MACHINE FOR FOUNDRY ART

Application filed June 5, 1928. Serial No. 282,910.

My invention has particular application to an apparatus for mixing and revivifying sand, loam and other ingredients used in foundry practice for making molds. The 5 general object of the invention is to provide an improved apparatus for the purpose of reducing the cost and labor of handling and conveying in the process of reconditioning used sand. This end I accomplish by the 10 provision of semi-automatic means for mixing, aerating and finally carrying off the materials used in making molds.

Supplementing these advantages are those derived from utilizing a reciprocating carrier 15 upon which the above described operations take place.

The various features of novelty which characterize my invention are pointed out with particularity in the detailed description which 20 follows. For a better understanding of the invention, however, its advantages and specific objects attained with its use, reference should be had to the accompanying drawings, in which I have illustrated and described a preferred embodiment of the invention.

Of the drawings:

Fig. I is a front elevation of the entire apparatus.

Fig. II is a plan view of the same.

30 Fig. III is a plan view of the sand cutters.

Fig. IV is a side elevation of the sand cutters and the apparatus for varying their position; and,

Fig. V is a side elevation of the sand plow.

35 With particular reference to Fig. I, the apparatus there illustrated comprises a carrier or table 1 for conveying the sand or other materials, storage bins or hoppers 2 from which the sand is deposited on the carrier 1, and the sand mixing and revivifying device comprehensively designed by the numeral 3. There is also shown the spiral plow 4 utilized for carrying off the materials from the carrier.

The carrier 1 is conveniently mounted on 45 wheels 5 so that it may be propelled back and forth along the track 6, a reversible motor 20 with remote control being employed to impart a reciprocating motion to the carrier through the medium of a speed reducer or 50 gearing train 31.

The sand mixing apparatus 3, which is best illustrated in Figs. III and IV, is mounted on a stationary frame 9, adjacent the carrier track 6. It comprises a pair of cutting cylinders 7, 8 having thereon a number of helical blades 10, the construction and position of the blades, as illustrated, being of a type now in use and forming no part of this invention. The cutting cylinders 7, 8 are shown mounted in bearings 21 at the ends of rocking levers or walking beams 11. The walking beams 11 in turn are centrally pivoted in bearings 22 and are rocked by means of a hydraulic ram 12, there being a pin 19 on the walking beam 11 movable in a cross-head 23 which is actuated by the rod 13. Guide rods 18 are employed to keep the rod 13 in proper alignment. Each cutting cylinder 7, 8 is revolved by means of a motor 14, mounted on the walking beam 11, power being transmitted through a chain 15 and sprocket wheel 16. The cutting cylinder 7 is designed to revolve in a clockwise direction as shown by the arrow, and its blades 10 are inclined to throw the sand or other material upward ahead of the cylinder as it revolves. In like manner the cutting cylinder 8 is designed to revolve in the opposite direction, and its blades are oppositely inclined. The shields 17 serve to prevent sand from being thrown by the cutters 7, 8 into the tilting mechanism.

Adjacent the carrier track 6 and mounted independently of the carrier 1 there is the sand plow or helical screw 4 used for the purpose of removing the sand from the carrier and depositing it to one side thereof into the pit 25, from whence it may be carried on a belt conveyor diagrammatically illustrated at 26. The plow 4 is independently driven by a motor 27, and the entire assembly may be elevated above the carrier 1. For this purpose I preferably employ an air hoist 28, but it will be obvious that other elevating means may be used with equal success. The preferred means for elevating and lowering the sand plow 4 are best shown in Fig. V. They comprise the air hoist 28 mounted on a beam 37 which is shown supported by complete columns 38 and which straddles the carrier track 6, and a series of pulleys 33 by means of which

the air hoist 28 actuates a cable 32. The ends of the cable 32 are attached to an I-beam 34 which in turn carries the plow 4 and its motor 27. At the ends of the I-beam 34 there are shown suitable guides 35 which co-operate with two vertical columns 36 to form a slide for the elevating and lowering of the sand plow 4.

Instead of a screw plow, I may employ a 10 blade inclined at an acute angle with respect to the edge of the carrier 1 approaching the blade on the side nearest the pit 25, or I may design the blades 10 of the cutting cylinders 7, 8 so that they throw the sand off the table 15 1 while mixing it.

Along the path of the carrier 1 and positioned close to the cutting cylinders 7, 8 are vertical shields 29 which serve to prevent the cutters from throwing sand beyond the 20 edges of the carrier, and beyond the shields 29 there are trimming plows 30 utilized to keep the sand pile in the center of the carrier 1.

The operation of the machine is as follows: 25 The carrier 1 is reciprocated beneath the hoppers or storage bins 2 which deposit thereon layers of predetermined quantity of the various sands to be mixed and aerated, the sand pile occupying nearly the full length of the carrier. The sand pile is then trimmed and the carrier 1 propelled in the direction shown by the arrow, the cutter 7 being in the lowered position. As the table moves beneath the cutter 7, the latter throws sand ahead of it mixing and aerating it, and by virtue of the shape 30 of the blades 10, the sand is moved toward the center of the carrier. When the carrier passes beyond the cutter 7 its movement is stopped, the rocking lever 11 is actuated by 40 the hydraulic ram 12 and the alternate cutter 8 is lowered to operative position. The carrier is then progressed in the opposite direction and the mixing operation continues. It will be readily apparent that the cutter 45 blades 10 are so formed that they are only effective when rotated in one direction. Accordingly by the use of interchangeable or alternate cutters, the carrier, when reciprocated, performs work as it progresses in either 50 direction. With the use of a single cutter, the cutter would only be effective when the carrier moves in one direction.

When the mixing and revivifying operation has been completed, the screw plow 4 is 55 lowered to the level of the sand pile and the carrier 1 moved in the direction of the arrow, thus clearing its platform of sand. Obviously, however, instead of removing the sand from the carrier, the carrier itself may 60 be utilized to convey the materials to another part of the foundry.

It will also be apparent that remote controls for the various motors, as well as the hydraulic ram 12 and the air hoist 28 for the 65 screw plow 4, may be located in a central po-

sition so that one operator may control and direct the entire operation. Furthermore, the operation of mixing and revivifying the sand is made a part of the conveying and handling operation so that the mixing machine together with the sand carrier and other appurtenances serves to transport the materials from the storage bins to remote parts of the foundry.

While the apparatus described is particularly adaptable for use in foundries in connection with the reconditioning of sand, it may be utilized to advantage in the mixing and conveying of granular materials of various description, and while I have illustrated and described the best form of my invention now known to me, it will be apparent to those skilled in the art that changes may be made in the form of the apparatus disclosed without departing from the spirit of my invention 85 as set forth in the appended claims, and that certain features of the invention may sometimes be used with advantage without a corresponding use of other features. For example, the carrier may be propelled by any mechanical means such as a winch and cable or a reciprocating engine; and in place of the screw plow shown for removing sand from the carrier, I may employ a scraper, a belt or other well known forms of apparatus for accomplishing this purpose.

Having thus described my invention, I claim:

1. A sand reconditioning machine of the class described, comprising a movable table carrying the sand to be reconditioned, a number of interchangeable cutting cylinders positioned above said table and independently thereof, means for revolving said cylinders, and means for reciprocating said table beneath said cutting cylinders whereby the sand is reconditioned.

2. In a sand reconditioning machine of the class described, a pair of rotary cutters, one of said cutters being adapted to revolve in a clockwise direction and the other in a counter-clockwise direction, and means for alternately positioning said cutters for effective operation.

3. In a sand reconditioning machine of the class described, a plurality of cylindrical cutters having rotary cutting blades, one of said cutters being adapted to revolve in a clockwise direction and another in a counter-clockwise direction, and means for alternately positioning said cutters for effective operation.

4. In a sand reconditioning machine of the class described, a pair of cylindrical cutters having rotary cutting blades, means for independently rotating said cutters each in a different direction, and means for alternately positioning each said cutter for effective operation.

5. A sand reconditioning machine of the

class described, comprising a reciprocatory platform for carrying sand to be reconditioned, a stationary frame adjacent said platform, a revolvable sand mixer mounted on said frame above the normal level of the sand, and means for lowering said mixer to operate on the sand as the platform is reciprocated under the sand mixer.

6. A sand reconditioning machine of the class described, comprising a reciprocatory platform adapted to be moved back and forth beneath a plurality of hoppers to receive successive layers of material to be reconditioned, a revolvable cutting cylinder mounted above said platform and independently thereof, and means for lowering said cylinder to operate on the material to be mixed as the platform passes beneath said cylinder.

7. A sand reconditioning machine of the class described, comprising a reciprocatory platform adapted to be moved back and forth beneath a plurality of hoppers to receive successive layers of material to be reconditioned, a revolvable cutting cylinder above said platform, a plow in advance of said cutting cylinder, said cylinder and plow being mounted independently of the platform and above the level of the materials on the platform, means for lowering the cutting cylinder to operate upon the materials on the platform, whereby the materials are mixed and aerated as the platform passes thereunder and means for lowering said plow, whereby the materials may be removed from the platform as it passes under said plow.

In testimony whereof, I have hereunto signed my name at Florence, New Jersey, this 31st day of May, 1928.

LOUIS A. CAMEROTA.
